UNITED STATES PATENT OFFICE

HERMAN BOCK, OF EAST ORANGE, NEW JERSEY

KEY CONTAINER

Application filed August 24, 1928. Serial No. 301,822.

The present invention relates to a key container.

An object of the present invention is to make an improved and simplified key container. In order to attain these objects there is provided, in accordance with one feature of the invention, a plurality of rigid plates having key supporting means carried thereby, said plates being connected to a flexible 10 backing member so as to be foldable one upon the other to reduce the area occupied by said container.

These and other features of the invention will be more fully brought out in the following description and the accompanying drawings, wherein:

Figure 1, is a view in front elevation of one form of the invention.

Figure 2, is a view in perspective of the device in a folded condition, and

Figure 3, is a view in perspective of the device in open condition showing one method of supporting keys thereon.

Referring to the drawings in detail:

25 A flexible cover member C has secured to each side thereof a rigid plate A secured to the flexible cover member as by means of rivets 11. In the present construction the metal plates are shown connected to each 30 other by means of a hinge connection 2 so as to be folded one upon the other as shown in Figure 2, to reduce the width of the device when folded for placing in the pocket. The upper end of each of the plates A is bent over to encircle a pin 3 upon which key supporting members 5 are mounted. These key supporting members comprise a wire member 6 having a looped upper portion 7 which encircles the pin 3 and a hook shaped lower portion 8 upon which a key 12 may be threaded.

45 The cover member C extends beyond the right hand rigid plate A as shown to provide a flap which may be brought over the edge of the device when folded and secured as by means of snaps 9 and 10 to hold the device in a folded condition.

50 The device is approximately one-half as wide as a key container having a single rigid plate of the combined width of the plates here

shown and having the same number of key supports and also requires considerably less material from which to form the cover member. This may be an important item when the more expensive materials are used for the 55 making of these cases.

While a specific type of hinge and key support are illustrated and described it is not desired to limit the invention to any specific construction of either of these portions of the 60 device since it would be a simple manner for any one skilled in the art to modify these old and well known features of the device without departing from the spirit of the invention as defined in the hereto appended 65 claim.

I claim:

A key container of the character described comprising a flexible cover member, a pair of hingedly connected plates connected adjacent an edge of said cover, a plurality of key support members carried by each of said plates said flexible cover being foldable in the axis of pivotal movement of said hingedly connected plates, and snap means to secure 70 said cover in a folded condition to enclose said hingedly connected plates and keys supported thereby.

In testimony whereof I affix my signature.
